MEANS FOR WRAPPING PACKAGES

Ernst A. Nordberg, Sharon, Mass., assignor to
Bandaway Inc., Boston, Mass.

Application March 9, 1938, Serial No. 194,910

3 Claims. (Cl. 93—93)

The present invention relates to a machine for wrapping bundles, particularly bundles containing cloth materials, as for instance, curtains, sheets, shirts or any other type of bundle in which it is desired to place a number of similar articles together as for instance in half dozen or dozen lots.

It has been common in wrapping such articles to use a strip cut to size, place the strip around the article to be wrapped and then either staple or glue the ends of the strip together. For the most part this has been done either entirely by hand or partly by machinery that is manually operated. The latter type of device is shown in the copending application of Sumner S. Gordon, Serial No. 176,421, filed November 26, 1937. In this application just mentioned, two operations are required to complete the wrapping, the operator first advances the paper or strip with a movement of the arm, and then, after placing the bundle in position, brings the two ends of the strips together and operates the stapling mechanism.

In the present application the feeding is done automatically and in such a manner that it will not interfere with the bundle that is previously being wrapped. Other purposes and advantages of the present invention will be more readily understood in connection with the specification given below describing an embodiment of the present invention illustrated in the drawing in which:

Figure 1 shows the present machine in an elevation.

Figure 2 shows a plan view looking from the top of Figure 1.

Figure 3 shows a sectional view taken on the line 3—3 of Figure 2.

Figure 4 shows a section view taken on the line 4—4 of Figure 1.

Figure 5 shows a section taken on the line 5—5 of Figure 4, and,

Figure 6 shows a section taken on the line 6—6 of Figure 3.

In the present invention the device may be mounted upon a bench or frame 1 as indicated in Figure 1 and comprises two upright supporting sides 2 and 3, the support 2 containing the strip feeding mechanism 4 for feeding the paper strips 5 from the roll 6. The strip feed mechanism 4 may be of the usual type comprising a series of rollers and gears through which the paper strip 5 is inserted and threaded with means provided for allowing the strip to be advanced and mechanism for repeating the operation of advancing and feeding the paper in determined lengths upon each operation of the device.

As indicated in Figure 1, the paper 5 is advanced between rollers 7 and 8 to the position of cutting and stapling by any usual and suitable

stapling machine in the manner as will be indicated below.

Two ears 9 and 10 extend respectively from the side supports 2 and 3 and pivot the shaft 14 upon which the arms 11 and 12 are mounted. The arms 11 and 12 at their other ends carry links 15 which connect from the arms 11 and 12 to the upright bar 16 of the stapling mechanism. Pivoted at the front portion of the bars 11 and 12 are two extending prongs or links 17 and 18, which as indicated in Figure 3 have pins 19 and 20 respectively which lock into the holes in the bars 11 and 12. These bars 17 and 18 are pivoted at their other ends by means of the pivots 21 and 22 to slide bars 23 and 24 respectively which slide bars may be operably connected to the foot lever 25 as will be described.

The stapling device 13 has a supply barrel 26 pivoted as indicated in Figure 1 in the support 27 extending from a base plate 28 fastened across from the side 2 to the side 3 of the frame, so that when the arms 17 and 18 are moved downward, the front portion of the stapling mechanism will descend downward and staple the paper that is positioned just beneath it. On the inside of the side elements 2 and 3 are grooved plates 30 and 31 in which the bars 32 and 33 slide up and down as indicated in Figure 3. These bars 32 and 33 at their lower ends are joined by the cross bar 34 from which the operating rod 35 extends which is linked at 36 to the foot lever 25. Also linked across the bars 32 and 33 is the bar 40, the purpose of which will be explained later. The bars 23 and 24 also slide respectively within the grooved plates 30 and 31. These bars are spanned by the cross bar 37 which carry pivoted at each end the latch or link mechanisms 38 and 39. Both latch elements 38 and 39 are pivoted as indicated in Figure 1 by the rod 37. These latch elements have a horizontally extending bar 41, 40 a vertical dependent member 42 which is cut in a C shape fashion with diagonally latching elements 43. A spring 44 bears down on the outer portion of the arm 41 holding the latch 43 in contact with the rod 40 and beneath it. In this position as indicated in Figure 1, the foot lever 25 is coupled to the stapling device through the latch 43 latching under the rod 40 carried by the bars 32 and 33 so that when the foot lever 25 is depressed the bars 23 and 24 and the links 17 and 18 to which they are joined will be moved

downward and carry with them the pivoted rods 11 and 12 which hold the stapling machine through the links 15. When the mechanism is pulled downward to force the arm 41 of the latching mechanism against the end of the screw 45 which may be adjusted to its proper position, the arm 41 will remain blocked while the rod 40 will continue to be drawn further downward, thus pushing aside the latch 43 until the rod 40 is 60

free of the latch end 43. When this occurs the stapling device is released and the spring 46 placed just beneath the stapling mechanism and which is compressed as the stapling mechanism descends forces the stapling mechanism back to its normal position by pressing upward under the cutting plate 47 at the base of the stapling machine. The little plates 80 held by screws 81 over the top of the slideways prevent the bars 10 23 and 24 from coming out of this slide. As the foot lever 25 comes down further, the cable 48 which has, during the operation described, travelled in the direction of the arrow 49, continues to travel in the same direction thereby allowing 15 the strip feeding machine to move in the direction of the arrow 50. This action positions the strip feeding mechanism so that when the lever 25 is again released and the spring 51 acts to pull the free end of the lever upwards, the strip feeding 20 mechanism will rotate in the direction opposite to the arrow 50 and cause the rollers 7 and 8 to move in such a manner as to again feed the strip 5 beneath the stapling device. When the rod 40 is in a position below the latch 43 the 25 upper mechanism is entirely free from the lower mechanism. When, however, the foot lever 25 is pulled upward by the spring 51, the rod 40 is moved upward and forces the latch 43 to the left in the position shown in Figure 1 and finally 30 rises above it in the position as indicated in Figure 1. The spring 44 serves to press the latch 33 back in its normal position by exerting pressure upon the arm 41 of the latch mechanism.

The cutting means is indicated more clearly in 35 Figures 4 and 5. The cutting plate 47 is mounted beneath the stapling device 13 and abuts in its normal position when not used against the upright extending posts 60 and 61 projecting from the lower cutting plate 62. The whole lower cutting plate is held in position against the upper plate by means the springs 63 and 64 which set in recesses in the base 65 of the lower plate and press against the lower plate 65 operating in 40 slots in the blocks 83 and 84 mounted on the side plates 2 and 3, by being mounted on the cross support 66 across the frames 2 and 3. As the 45 stapling means is brought downward the cutting edges 70 of the upper and lower plates come together with the lower plate always pressed against the upper plate by means of the actions of the 50 springs 63 and 64 so that even though the plates wear, their edges are always insured of being together.

In the operation of the mechanism, the operator threads the strip 5 through the strip feeding mechanism bringing the paper between the cutting and stapling jaws.

A proper guide plate may be used to guide the strip to this position. The strip feeding mechanism as in the previous companion application is set for the desired length of strip. The apparatus is then ready to be used and the operator may press the foot lever in order to advance initially the strip for the proper length. This 60 strip is then placed around the package to be wrapped and the end of the strip brought back upon the strip itself underneath the stapling head. The operator then again presses the foot lever 25 which staples the two ends of the strip together and holds the foot lever in the lower 65 position until the package is removed. When the foot lever is raised the mechanism holding the strip feeding device is thereby released and as the lever comes up, the strip is fed in position

for the operator to place the second bundle to be wrapped over the strip. The operator then brings the end of the strip back to the strip again and the stapling is repeated in the same manner as previously described. The operator therefore in handling the machine needs only to bring the end of the strip back upon itself and press the foot lever once to complete and finish the wrapping of the package.

Having now described my invention, I claim: 10

1. A machine of the type described comprising in combination a strip serving device and a stapling device having a stapling head, means pivoting said stapling device at the end away from the stapling head, a foot treadle for pulling the stapling head down for stapling the strip served, means normally connecting the treadle to said head, said means comprising means attached to said head having a vertically sliding bar, a pivoted latch mechanism attached to said sliding bar, a cross bar attached to said treadle normally engaging said pivoted latch, means operative upon drawing the treadle down for releasing the cross bar from said latch and thereby releasing said stapling head and means operatively connecting said strip serving device with said treadle for advancing the strip from the strip serving device upon the release of the treadle. 25

2. A machine of the type described comprising in combination a strip serving device and a 30 stapling device having a stapling head, means pivoting said stapling device at the end away from the stapling head, a treadle for pulling the stapling head down for stapling the strip served, means normally connecting the treadle to said 35 head, said means comprising a yoke having arms extending downward at the end of the yoke, means for guiding the motion of said arms in a vertical direction, a latch mechanism pivoted at the end of each of said arms, a cross bar normally engaging said latch, a frame positioned in 40 said guideway in which said bar is pivoted and means connecting said frame to said treadle, means operative upon drawing the treadle down for releasing the cross bar from said latch and thereby 45 releasing said stapling head and means operatively connecting said strip serving device with said treadle for advancing the strip from the strip serving device upon the releasing of the treadle. 50

3. A machine of the type described comprising in combination a strip serving device and a stapling device having a stapling head, means pivoting said stapling device at the end away from the stapling head, a foot treadle for pulling the 55 stapling head down for stapling the strip served, means normally connecting the treadle to said head, said means comprising means attached to said head having a vertically sliding bar, a pivoted latch mechanism attached to said 60 sliding bar, a cross bar attached to said treadle normally engaging said pivoted latch, means operative upon drawing the treadle down for releasing the cross bar from said latch and thereby releasing said stapling head and means operatively connecting said strip serving device with 65 said treadle comprising a belt means connected to the opposite side of the treadle to which the stapling head is connected and means adapted to move said belt in a direction opposite to the 70 direction of the connection to said stapling head whereby the strip from the strip serving mechanism is served upon the releasing of the treadle.
